UNITED STATES PATENT OFFICE

GEORGE E. COUTANT, OF DECATUR, ILLINOIS

RAILWAY-CAR SIDE DOOR

Application filed August 2, 1928. Serial No. 296,943.

My device relates to a railway car having a door opening in its side wall and a door arranged to move horizontally to close the door opening. Such a door may be supported upon the side sill by brackets with anti-friction rollers mounted therein, (as illustrated) or it may be supported by suspension hangers engaging a track supported by the side plates adjacent the top of the door opening. The front vertical edge of the door is provided with a stiffener or frame member having a tongue or extension which engages a front door stop mounted on the front door post and the rear vertical edge of the door is provided with a stiffener or frame member having a tongue or extension which engages a rear locking strip mounted on the rear door post. These front and rear tongue engagements form weatherproof and burglar-proof joints. The upper horizontal edge of the door is provided with a stiffener, frame member or a top interlocking strip and the bottom edge is provided with a frame member of perhaps a bottom track with a vertical depending lip behind the supporting bracket (as illustrated).

The front, rear, top and bottom stiffeners may be secured together at the corners of the door to form a rectangular frame. It is common practice to stiffen the four sides of a wooden door with such frame members and to stiffen the wooden door with battens, stiles and intermediate horizontal metal stiffening strips, but my device is an improvement thereon and contemplates the use of a relatively thin metallic plate rigidly secured to such a frame (or formed integral therewith) and may be reinforced with integral horizontal, vertical or diagonal corrugations or embossments formed therein which transmit any loads or thrusts imposed thereon to the frame members. A side door is subjected to quite a few forces which have a tendency to distort the rectangularity of the door and cause buckling stresses in the door body plate. Such forces are caused by the door being moved suddenly to a closed position when either the upper corner or lower corner of the door strikes the front door stop before the other corner does. This condi-

tion is caused by the door opening being out of square. Such forces are also caused when the door suddenly hits the back door stop an eccentric blow. The crow-bar when used to open a door is another source of trouble. 55

Considerable difficulty is experienced by the shearing of the rivets which secure the metallic plate to the frame members or stiffeners. This is caused by the rivet heads hitting the frame members of the car when being moved horizontally to open or closed position. It is not unusual for a rivet head to come in contact with a door post, whereupon the hasp is put over the staple and hit with a sledge, causing a sheared rivet or broken hasp. Countersunk rivets in such a thin metallic sheet are impracticable. (Such sheets are usually $\frac{1}{16}$ " thick.) 60 65

The object of the invention is to provide a door for a railway freight car made of a thin metallic sheet, having stiffening members riveted to one or more margins thereof, and to offset said margin or margins so that the heads of the rivets will be within the plane bounding the main body of the door so that such rivet heads will clear the car body when moving to open or closed position; or in other words, the main body of the door sheet will prevent the rivet heads from striking the car body. 70 75 80

Another object is to protect the front or back spark strip by positioning it adjacent the vertical door stiffener (or securing it thereto) so that any blow upon the spark strip will be partially transmitted to the stiffener. 85

Figs. 1, 2, 3 and 4 show sections through front, back, top and bottom, respectively, of my preferred construction.

Figs. 5, 6, 7 and 8 show a modified construction. 90

Figs. 9 and 10 show another modified construction.

Fig. 11 shows a horizontal section through a car wall having a door according to my invention. 95

Fig. 12 shows an assembled door.

In the drawings the usual parts of the car are shown, such as, side sill 1, floor 2, floor support 3, side plate 4, door hood 5, front 100

door post 6, rear door post 7, front spark strip or door stop 8, rear spark strip 9, nailings strips 10, sheathing 11 and lintel 12.

The side door sheet comprises a body portion 20 with offset portions at front (21), rear (22), top (23) and bottom (24).

The front stiffener 25 is secured to the front offset portion 21 with round head rivets 26, and is formed with a tongue 27 which enters the recess 28 formed by the strip 8 and door post 6. This tongue is substantially flush with the body portion 20 of the sheet. A stiffening flange 29 may be provided.

The rear stiffener 30 is secured to the rear offset portion 22 by the round head rivets 31, and is formed with a flange 32 which engages the rear spark strip 9. A stiffening flange 33 may be provided.

The top stiffener 35 is secured to the top offset 23 by rivets 36 and interengages with the hood 5. The inside wall 37 of the stiffener is substantially flush with the sheet body portion 20. A door hanger 38 for top hung doors is shown in dotted lines in Figure 3.

The bottom stiffener 40 is secured to the bottom offset portion 24 by rivets 41. The inner flange 42 is substantially flush with the body portion 20 of the door sheet. A bottom supporting roller 43 and its bracket 44 is shown but, of course, my invention may be used with either a top or bottom supported door.

In the described front and top constructions, the rivet heads are positioned within the recess 46 formed by the offset and the stiffener and are of less depth than the recess.

When the door is moved horizontally to open or close it, the inner wall 37 of the top stiffener 35 rubs against the lintel 12, thus preventing the top rivets 36 from hitting the car body, particularly the door posts. The tongue 27 of the front stiffener 25 rubs against the floor 2 and lintel 12 thus protecting the rivets, and likewise the body portion 20 of the sheet rubs against the rear door post 7 and holds the rivets away from the car body. It is not necessary to the invention that all of the above described constructions be used in the same door.

In the modified constructions shown in Figs. 5, 6, 7, 8, and 12, the door sheet is reinforced by an integral corrugation 60 adjacent each margin which is reinforced by a lattice 61 to form a box girder and a rear door spark strip 62 is used. In the modified constructions shown in Figs. 9 and 10, a separate corrugated plate 63 is riveted to each vertical margin of the door sheet and reinforced by a flat sheet 64 to form a box girder, and a separate rear spark strip 65 is used.

The striking of the rear spark strip 62—65 against the rear stop 9 (on the car body) bends and twists the rear spark strip, there-

fore, when a corrugated stiffener, or any separate stiffener is used, I prefer to extend the door spark strip to engage the stiffener as shown at 70 in Figs. 9 and 10, or in fact, it may be desirable to secure it, the stiffener, as shown by rivets 71 in Figs. 5 and 6. The lattice 61 makes it possible to drive the rivets. Fig. 11 shows a casting 72 which transmits the blow to both the spark strip and stiffener. This casting engages the stop 73 on the car body.

The drawings illustrate the preferred form of the invention, though it is to be understood that the invention is not limited to the exact details of construction shown and described, as it is obvious that various modifications thereof within the scope of the claims will occur to persons skilled in the art.

I claim:

1. In a railway car, the combination of a stop on the car body, a horizontally movable door comprising a metallic sheet, a stiffener having a laterally extending portion and secured to said sheet adjacent one margin thereof by round head rivets and a member arranged to engage said stop and arranged to transmit any blow thereon to said portion, said margin being offset so that when the door is being moved into open or closed position the body of the sheet will prevent the rivet heads from striking the car body.

2. A door for a railway car comprising a metallic sheet having an outwardly offset portion adjacent each vertical and horizontal edge, a member secured to each of said portions having a stiffening flange projecting in the same direction as said offset portions, and another stiffening flange projecting in the opposite direction from said offset portions.

3. A metallic door for a railway car provided with a continuous corrugation adjacent the edges thereof, and a plurality of embossments with their opposite ends merging into parts of said corrugation, the marginal portion of the door adjacent said corrugation being in a different plane than the central portion of the door.

4. A metallic door for a railway car provided with a corrugation adjacent each opposite edge thereof, and a plurality of embossments normal to and merging into said corrugations, the marginal portion of the door adjacent said corrugation being in a different plane than the central portion of the door.

GEORGE E. COUTANT.
